DESIGN FOR A COMBINATION CAP AND COMB

Albert E. Sierad, Larchmont, N. Y.

Application August 26, 1944, Serial No. 115,052

Term of patent 14 years

(Cl. D86—8)

To all whom it may concern:

Be it known that I, Albert E. Sierad, a citizen of the United States, residing at Larchmont, in the county of Westchester and State of New York, have invented a new, original, and ornamental Design for a Combination Cap and Comb, of which the following is a specification, reference being had to the accompanying drawing, forming part thereof.

In the drawing:

Fig. 1 is a side elevational view of a combination cap and comb, showing my new design;

Fig. 2 is a central longitudinal sectional view of Fig. 1.

Fig. 3 is a bottom plan view thereof.

I claim:

The ornamental design for a combination cap and comb, substantially as shown.

ALBERT E. SIERAD.
